UNITED STATES PATENT OFFICE.

SAMUEL E. DIESCHER, OF PITTSBURGH, PENNSYLVANIA, ASSIGNOR TO S. DIESCHER & SONS, A COPARTNERSHIP CONSISTING OF SAMUEL E. DIESCHER AND AUGUST P. DIESCHER, OF PITTSBURGH, PENNSYLVANIA.

APPARATUS FOR TREATING SHEETS.

Application filed July 2, 1923. Serial No. 649,168.

After sheets have been reduced in the hot mill to the desired gauge, they are arranged in packs and annealed. As in this annealing operation all portions of each sheet should be brought to an annealing heat, and as each pack consists of a large number of sheets, the penetration of heat to the interior of the packs requires a long time, and at that, the pack must be subjected exteriorly to the temperature above the required annealing temperature. The annealing temperature is such that there is a tendency for the plates to stick and if the required temperature is exceeded, the tendency for plates to stick together is increased in proportion.

The prevailing method employed for separating stickers consists in hammering the top sheet of the pile, as it comes out of the annealing pot, which is done by hand with a sledge. In such hammering, the central portion of the top of the pack is first operated on and then portions around the center, each circular series of blows being more distant from the center than the preceding series. As will be readily understood by those skilled in the art, each impact of the hammer will cause a flow of the metal in practically all directions from the point of impact and the flow will be greatest in the sheet struck by the hammer and decreasing inwardly of the pile. By reason of this difference in flow adjacent sheets will move relative one to the other, rupturing the bond between the sheets. While this method is effective to rupture the bond between sheets, it involves heavy labor and considerable time as a dozen or more blows are required in most cases. And further, as the metal will flow in all directions from the point of impact and as the hammer is raised after each blow, it follows that flow from each blow will extend into portions which have already been treated. After the hammering, such a pack of sheets as may have been loosened, are removed from the pile for separation by hand.

The invention described herein has for its object the provision of means for subjecting the pile of sheets to the impacts necessary for effecting sufficient flow of metal to rupture the bonds between sheets, the blows being imparted over substantially the entire area of the top of the pile at one operation, the initial blow being delivered at approxi-

mately the center of the top of the pile and the other blows in sequence at suitable distance from the point of initial impact. It is a further object of the invention to control the direction of the effect produced by the blows subsequent to the initial blow. The invention is hereinafter more fully described and claimed.

In the accompanying drawing forming a part of this specification, Fig. 1 is a plan view of a hammer mechanism embodying the improvement claimed herein; Fig. 2 is a view showing a portion of the carrying frame and showing the hammer portion of the mechanism in section; Fig. 3 is a sectional elevation of the hammer head; Fig. 4 is a sectional view on the plane indicated by the line IV—IV, Fig. 2; Fig. 5 is a sectional view on the plane indicated by the line V—V, Fig. 3 looking up; Figs. 6 and 7 are views similar to Figs. 3 and 4 illustrating a modification of the construction of the hammer head.

The hammering mechanism and the means for operating the same are arranged within a frame 7 preferably supported by a truck so that the hammer mechanism may be moved from place to place. By reference to Figs. 1 and 4 it will be seen that one end of a frame 7 extends beyond its support, and to the projecting portions of the frame are secured guide members 17 for the hammer head, as hereinafter described. These guides should be spaced a distance apart approximately equal to one of the horizontal dimensions of the pile so that said guide will pass along opposite sides of a pile when the frame is shifted, thereby ensuring the vertical alinement of the hammer head with the pile to be operated on.

The hammer head consists of a lifting shell 18 enclosing a plurality of percussors or hammer bars, so supported in the shell as to be capable of independent vertical movement. As shown in Fig. 6 the shell is provided with ribs 19 adapted to engage the guides 17 and at one end with a yoke 20 adapted to be connected with a suitable lifting mechanism as will be hereinafter described. The percussing elements consist of metal bars 21 provided at their ends with cylindrical reduced portions 22 and 23 which when the parts of the head are assembled, extend through openings in the heads of the

shell 18. It will be observed that the cylindrical portions 23 of the bars *a* at the center of the shell are longer, measured from the shoulders *x* than the corresponding parts 5 of the bars *b* surrounding the bars *a*, and that the cylindrical parts 23 of the bars *c*, outside of the bars *b*, are shorter than the parts 23 of the bars *b*. It follows from such construction that when the head is dropped, 10 the bars *a* will hit the pile of sheets in advance of the bars *b* and the latter in advance of the bars *c*. In order that the downward movement of the shell and consequently the bars may not be checked by the bars *a* when 15 their movement is arrested by contact with the pile of sheets, the necks 22 at the upper ends of the bars vary in length proportional to the distance of the respective bars from the center line of the head. As the shell enclosing 20 the percussing bars is of considerable weight, a sudden stoppage of its downward movement would produce a severe jar or shock, and to avoid such jar, springs 24 are placed on the necks 22, the shoulders *y* on 25 which the lower ends of the springs bear being so located on the several bars and the springs made of such lengths that the upper head of the shell will bear simultaneously on all the springs.

30 In lieu of the construction of hammer head having one or more central percussion bars and one or more annular series of bars as shown in Figs. 5, 6, and 7, the construction shown in Figs. 8 and 9 may be employed. As shown, the hammer head consists of a lifting shell 18^a, a central hammer bar *d* and one or more annular bars *e* and *f*. In order to connect the hammer bars to the 35 shell for effecting the upward movement of the bars, the latter are slotted diametrically as shown at 70 and through the slots in the several bars is passed a cross-pin 71 having its ends secured in the shell. It will be observed that the slots in the respective bars 40 are made of such relative lengths that although the inner members strike the packs first, the outer members can continue their 45 downward movement.

50 The effect of the impact of a bar will be greatest on the top sheet of a pile and will decrease progressively on underlying sheets. When a blow is struck, the metal of the top sheet for an area approximately equal to that of the face of the bar will be stretched; 55 the next sheet will also be stretched but to a less degree than the top sheet and there will be a movement of one sheet relative to the other. If the contacting faces of the sheets around the area effected by the blows, 60 are adhering, the stretching will produce a buckling effect and when the next series of bars strike a sheet, they will also produce a stretching and buckling of sheets, but as the bar at the center remains in contact with the 65 top sheet and is quite heavy, it will prevent

the buckling due to the action of the second series of bars, extending inwardly.

While any suitable means may be employed for raising the hammer head, and then permitting it to drop, it is preferred to 70 employ mechanism such as shown herein. A flat member 25 preferably a hardwood plank and having one end secured to the yoke 20 projects upwardly between rollers 26 and 27 75 having their journals mounted in rotatably mounted blocks 26^a and 27^a, the openings through said blocks 26^a and 27^a being eccentric, to the cylindrical body of the blocks 26^a and 27^a. The blocks 26^a, carrying the journals of the roller 26 are provided with 80 radial arms 28 which are connected by links 29 to arms 30 on the shaft 31 to which is secured an operating lever 32. The blocks carrying the journals of the roller 27 are provided with radial arms 33 connected by 85 links 34 to arms 35 on the shaft 36 which also is provided with an arm 37 connected to a threaded rod 38 passing through an opening through a rotatable plug 39 and provided with an operating wheel 40 which contains a nut for the rod 38. By rotating the blocks 26^a and 27^a the rollers can be moved 90 towards and from each other. Before operating the mechanism the blocks 27^a are inserted to insure an operative grip on the 95 rollers on the member 25. The blocks 26^a are shifted by the lever to cause the roller 26 to grip the member 25 to raise the hammer head or to release said member thereby 100 permitting the hammer head to drop. In order to prevent the head being drawn up too high in case the operator fails to shift the lever 32, provision is made for shifting the roller 26 out of contact with the member 25 when the hammer head has been raised 105 a predetermined height. As shown in Fig. 4, an arm 41 on the shaft 31 is connected by a link 42 to an arm 43 on a shaft 44 which is provided with an arm 45 projecting into a path of movement of the shell 18 of the 110 hammer head. When the shell 18 in its upward movement strikes and shifts the arm 45, the shaft 31 will be rotated in a direction to move the roller 26 away from the element 25. From the foregoing it will be clear that 115 the lifting of the hammer head is controlled by the operator through the lever 32, and that the lifting movement may be checked by the operator or automatically through the shifting of the shaft 31 by the hammer head as 120 described.

One of the journals of each of the rollers 26 and 27 are extended sufficiently far beyond its bearing for the reception of pulleys 46 and 47, which are driven in such direction 125 that the rollers will rotate in opposite directions.

Provision is made for the control of the dropping of the hammer head by the operator. The upper portion of the element 25 130

is extended up between means permitting the upward movement of the element 25 but adapted to grip the element when the latter moves downwardly. A suitable construction to that end consists of a dog 50 so pivotally mounted that its free end will move upward with the element 25 but its downward movement is checked by a stop 51, and a roller 52 having eccentric journals 53 arranged on the opposite side of the element 25. On one of the journals of the roller 52 is secured an arm 54 which is connected by a rod 55 to a treadle 56. These parts are so combined that when the treadle is depressed the roller will be rotated in a direction to release the element 25 carrying the hammer head. In order to compensate for wear of the parts especially the element 25, which as stated, is preferably made of wood, provision is made for adjusting the dog 50 relative to the roller. To this end the pivotal shaft 57 of the dog 50 has its ends arranged in slots, to permit of the dog being shifted longitudinally by a wedge 59 which has its upper end pivotally connected to a lever 60. The free end of the lever is connected to the upper end of the rod 61 having its lower portion threaded to engage the thread provided for its adjustment in the hub of the hand wheel 63.

As will be understood by those skilled in the art, the improvement claimed herein embodies a plurality of hammer bars, means for lifting said bars such as the rollers 26 and 27, and means whereby the bars may be detachably connected to the lifting means, such connecting means being adapted in its upward movement to engage the bars at such points that some of the bars will be raised greater distances than others.

I claim herein as my invention:

1. In an apparatus for treating sheets, the combination of a plurality of vertically arranged hammer bars adapted to operate independently one of the other and in such succession as to cause a flow of metal toward the edges of the sheet.

2. In an apparatus for treating sheets the combination of a plurality of hammer bars and means for so operating the hammers in succession that the initial point of impact on the sheet will be distant from the edges thereof and succeeding points of impact more closely adjacent to an edge of the sheet.

3. In an apparatus for treating sheets the combination of a plurality of hammer bars,

means for so operating the hammers in succession that the initial point of impact on the sheet will be distant from the edges thereof and succeeding points of impact more closely adjacent to an edge of the sheet and occurring while the priorly operating bars are in contact with the sheet. 65

4. In an apparatus for treating sheets the combination of a plurality of vertically arranged hammer bars, vertically movable means adapted to engage the bars during the upward movement of such means and means for releasing the bars from the vertically movable means.

5. In an apparatus for treating sheets the combination of a plurality of vertically arranged hammer bars and means adapted to raise some of the bars a greater distance than others. 75

6. In an apparatus for treating sheets the combination of a plurality of vertically movable hammer bars arranged in concentric series and adapted to operate in succession. 80

7. In an apparatus for treating sheets, the combination of a plurality of gravity hammers and means for lifting said bars, the bars and lifting means being so constructed and operated that when the bars are raised the operative ends of adjacent bars will be at different distances from the surface of the article operated on. 90

8. An apparatus for treating sheets having in combination a plurality of vertically movable hammer bars arranged in concentric series and means for raising the outer series a greater distance than the bars of 95 the inner series.

9. An apparatus for treating sheets having in combination a plurality of hammer bars, lifting means, and means adapted to be detachably engaged by the lifting means 100 and adapted when moved upwardly to engage the bars at different points from their lower ends.

10. An apparatus for treating sheets having in combination a shell, a plurality of hammer bars arranged within the shell, the lower ends of the bars extending beyond the shell, means for lifting the shell and means for so connecting the shell to the bars, when the shell is moved upward, that some of the bars will be raised a greater distance than other bars. 105

In testimony whereof, I have hereunto set my hand.

SAMUEL E. DIESCHER.
